UNITED STATES PATENT OFFICE.

WILLIAM A. LOTZ, OF NEWARK, NEW JERSEY, ASSIGNOR TO THE E. NEUMANN HARDWARE CO., A CORPORATION OF NEW JERSEY.

BAG HANDLE AND HANDLE FASTENER THEREFOR.

1,427,608.

Specification of Letters Patent. Patented Aug. 29, 1922.

Application filed May 18, 1921. Serial No. 470,512.

To all whom it may concern:

Be it known that I, WILLIAM A. LOTZ, a citizen of the United States, residing at Newark, in the county of Essex and State 5 of New Jersey, have invented certain new and useful Improvements in Bag Handles and Handle Fasteners Therefor; and I do hereby declare the following to be a full, clear, and exact description of the invention, such as will enable others skilled in the art to which it appertains to make and use the same, reference being had to the accompanying drawings, and to characters of reference marked thereon, which form a 10 part of this specification.

This invention has reference to improvements in handles for travelling bags, suit-cases, and the like; and, the present invention relates, more particularly, to a 20 novel form and construction of handle-fasteners for attaching the handle to a bag-frame.

The principal object of the present invention is to provide a means for detachably 25 securing the ends of a bag-handle to the frame of a bag, suit-case, or the like; and, the invention has for its further object to provide a novel and simply constructed handle-fastener for bag-frames, whereby, 30 should the handle become worn, torn or soiled, it can readily be detached, without having to remove the handle-fasteners from the bag-frame section, and readily replaced by another handle.

35 Other objects of the present invention not at this time more particularly enumerated will be clearly understood from the following detailed description of the present invention.

40 With the various objects of the present invention in view, the said invention consists, primarily, in the novel handle-fastener hereinafter more fully set forth; and, the said invention consists, furthermore, in the 45 novel arrangements and combinations of the various devices and parts, as well as in the details of the construction of the said parts, all of which will be more fully set forth in the following specification, and then 50 finally embodied in the clauses of the claims which are appended to and which form an essential part of the said specification.

The invention is clearly illustrated, in the accompanying drawings, in which:—

55 Figure 1 is an elevation of a fragmentary

portion of a bag-frame section, and a pair of handle-fasteners secured upon said frame-section, with a bag-handle detachably secured at its ends to said handle-fasteners, all arranged to show one embodiment of the 60 principles of the present invention.

Figure 2 is a top view and Figure 3 a bottom view of one of the handle-fasteners; Figure 4 is a longitudinal vertical section of the same, said section being taken on line 65 4—4 in said Figure 2, looking in the direction of the arrow *x* in said Figure 2; and Figure 5 is a similar view of the said fastener, said section being taken on line 5—5 in said Figure 2. 70

Figure 6 is a sectional view of the fastener, similar to that represented in said Figure 4, but showing the parts in their operated positions, for the attachment of an end of a bag-handle to the fastener, or for 75 its removal therefrom; and Figure 7 is a transverse vertical section of the fastener, said section being taken on line 7—7 in said Figure 2, looking in the direction of the arrow *y* in said figure. 80

Figure 8 is a top view, and Figure 9 a bottom view of a handle-fastener of a slightly modified construction, but still made according to and embodying the principles of the present invention. 85

Figure 10 is a side elevation of said handle-fastener; and Figure 11 is a longitudinal vertical section of the same.

Figure 12 is a similar section of the said fastener, showing the parts thereof in their 90 operated positions, for the attachment to or removal from said fastener of an end of a bag-handle.

Similar characters of reference are employed in all of the said above described 95 views, to indicate corresponding parts.

Referring now more particularly to several figures of the drawings, the reference-character 1 indicates one of the usual bag-handles with the ends of which are 100 suitably connected the usual handle-loops 2. The reference-character 3 indicates the novel form of handle-fastener, the same comprising a suitably formed box or shell consisting of a top 4, a pair of longitudinally extending 105 sides 5, and laterally extending ends 6, the latter being provided with downwardly projecting lugs or ears 7, adapted to be inserted through suitably disposed slits in the frame-section 8, and bent against the inner face 110

of said frame-section, substantially as indicated in Figure 1 of the drawings.

As shown, the said top 4 is preferably formed with a laterally extending and outwardly convexed portion, as 9, formed with suitably disposed slits 10, for the purposes to be presently more fully described. Extending laterally across the chamber formed by the top, ends, and sides of the said box or shell, and directly beneath the said slits, is a pin 11, which has its ends inserted and suitably secured in perforations 12 with which the said sides 5 are provided, substantially as shown in Figure 7 of the drawings. Pivottally mounted upon said pin 11 is a latch, consisting of a suitably curved or bent body-plate 13, the free end 14 of which provides a suitable fingerpiece. Curving from the opposite marginal edges of said body-plate 13, as at 15, are a pair of ribs or projections 16, the lower end-portions 17 of which extend through the respective slits 10, said ends 17 being made in the form of pivot-lugs or ears and being perforated, as at 18, for pivotally mounting said latch upon the said pin 11, substantially as shown in the several figures of the drawings. Suitably secured within the said box or shell, by means of a rivet 19, or otherwise, is a plate or member, as 20, a spacing washer 121 being preferably mounted upon the shank of said rivet, between the upper surface of said plate or member 20 and the inner surface of the top 4, as shown. At its portion nearest the said latch, the said plate or member 20 has an upwardly extending element or post, as 21, extending into and through a laterally extending slit 22 in the top 4 of the box or shell, and being of the same width, or approximately so, as the width of the body-plate 13 of the latch. At its upper portion, outside of the said box or shell, the said element or post 21 is made with a curved and slightly downwardly projecting handle-loop receiving or carrier-element 23, with the end edge-portion of which the portions 15 of the ribs 16 are adapted to be brought into closing engagement, as shown in Figures 1, 2, 4 and 5 of the drawings. This closing engagement of these parts is automatically produced by a coiled spring 24 mounted upon the previously mentioned pin 11, one end 25 of said spring being in engagement with the plate or member 20, and the other end-portion 26 of said spring being in engagement with a projection or finger, as 27, extending forwardly and transversely from one of the ears or pivot-lugs 17 of the hereinabove mentioned latch, and as clearly represented in Figures 3, 4 and 5 of the drawings.

In practice, two of such shells or boxes are secured upon one of the hinged frame-sections of a bag-frame, in the desired positions, and in the manner shown in Figure

1 of the drawings, the latches of the respective fasteners being suitably swung upon their pivot-ears or lugs 17, outwardly, against the actions of the springs 24, see Figure 6, to permit of the placing of the respective handle-loops 2 beneath the respective loop-receiving or carrier-elements 23 of the two handle-fasteners, as will be evident. As soon as the pressure is released from the opened latches, the springs 24 cause them to be automatically brought into closed engagement with the elements 23, thereby properly and securely attaching the handle to the bag-frame, as will be clearly understood.

In the modified construction of handle-fastener shown in Figures 8 to 12 inclusive, the general arrangement and construction of the several parts is the same as that described in connection with said Figures 1 to 7 inclusive, except in lieu of the coiled spring 24, I secure by means of the rivet 19, against the lower face of the plate or member 20, a flat spring, as 28, the forward end-portion 29 of said spring being adapted to engage either of a pair of angularly disposed edge-portions 30 or 31 of the respective pivot-ears or lugs of the latch, whereby the several parts of the handle-fastener are adapted to be brought into their relatively closed positions, as indicated in Figures 10 and 11, or into their opened positions, as illustrated in Figure 12, the spring holding the latch in either position, until actuated by the operator for closing or opening the handle-loop receiving or carrier-element, as will be clearly evident.

Any further description of this form of handle-fastener is therefore deemed unnecessary.

Of course I am aware that some changes may be made in the general arrangements and combinations of the several devices and parts, as well as in the details of the construction of the said parts, without departing from the scope of the present invention as set forth in the foregoing specification, and as defined in the clauses of the claims which are appended thereto. Hence, I do not limit my present invention to the exact arrangements and combinations of the several devices and parts as described in the said specification, nor do I confine myself to the exact details of the construction of the said parts, as illustrated in the accompanying drawings.

I claim:

1. In combination with a bag-frame-handle provided at its ends with handle-loops, handle-fasteners adapted to be secured upon a bag-frame, each handle fastener comprising a chambered box, a loop-receiving carrier-member non-separably secured with in each box and having a carrier-post extending above said box, said posts being

formed with curved receiving members with which the ends of the handle are detachably connected, and latches connected with said fasteners adapted to be brought into engagement with said receiving-members.

2. In combination with a bag-frame handle, provided at its ends with handle-loops, handle-fasteners adapted to be secured upon a bag-frame, each handle fastener comprising a chambered box, a loop-receiving carrier-member non-separably secured within each box and having a carrier-post extending above said box, said posts being formed with curved receiving members with which the ends of the handle are detachably connected, and spring-controlled latches pivotally connected with said fasteners adapted to be brought into engagement with said receiving-members.

20 3. A handle-fastener comprising a chambered shell or box adapted to be secured upon a bag-frame section, a loop-receiving carrier-member non-separably secured within said box and having a carrier-post extending from and above said shell or box, said post being provided with a curved receiving member, a pin within said shell or box, and a latch pivoted upon said pin, said latch extending from and above said shell or box and adapted to be brought into engagement with said receiving-member.

4. A handle-fastener comprising a chambered shell or box adapted to be secured upon a bag-frame section, a loop-receiving carrier-member non-separably secured within said box and having a carrier-post extending from and above said shell or box, said post being provided with a curved receiving member, a pin within said shell or box, and a latch pivoted upon said pin, said latch extending from and above said shell or box, and a coiled spring encircling said pin, said spring having a portion in engagement with said latch for forcing the latter into engagement with said receiving-member.

45 5. A handle-fastener comprising a chambered shell or box adapted to be secured upon a bag-frame section, a loop-receiving carrier-member non-separably secured within said box and having a carrier-post extending from and above said shell or box, said box being provided with a curved receiving member, a pin within said shell or box, and a latch pivoted upon said pin, said latch ex-

tending from and above said shell or box, a coiled spring encircling said pin, and a finger extending from said latch with which a portion of said spring is in engagement for forcing the latch into engagement with said receiving-member.

60 6. A handle-fastener comprising a chambered shell or box adapted to be secured upon a bag-frame section, a hook-shaped loop-receiving carrier-member connected with and extending from said shell or box, a pin within said shell or box, a latch provided with marginal ribs, perforated pivot-ears extending from said ribs for pivoting said latch upon said pin, said ribs being adapted to be brought into closing engagement with the hook-shaped portion of said carrier-member.

65 7. A handle-fastener comprising a chambered shell or box adapted to be secured upon a bag-frame section, a hook-shaped loop-receiving carrier-member connected with and extending from said shell or box, a pin within said shell or box, a latch provided with marginal ribs, perforated pivot-ears extending from said ribs for pivoting 70 said latch upon said pin, a coiled spring encircling said pin, said spring having a portion in engagement with said latch for forcing the latter into engagement with said carrier-member.

80 8. A handle-fastener comprising a chambered shell or box adapted to be secured upon a bag-frame section, a hook-shaped loop-receiving carrier-member connected with and extending from said shell or box, a pin within said shell or box, a latch provided with marginal ribs, perforated pivot-ears extending from said ribs for pivoting 85 said latch upon said pin, a coiled spring encircling said pin, and a finger extending from one of said pivot-ears with which a portion of said spring is in engagement for forcing the ribs of said latch into closing engagement with the hook-shaped portion of said carrier-member.

90 In testimony, that I claim the invention set forth above I have hereunto set my hand this 16th day of May 1921.

WILLIAM A. LOTZ.
